James R. Gibbons Inventor

UNITED STATES PATENT OFFICE.

JAMES N. GIBSON, OF GREELEY, COLORADO.

OIL-TANK FOR DELIVERY-WAGONS.

SPECIFICATION forming part of Letters Patent No. 781,719, dated February 7, 1905.

Application filed July 15, 1904. Serial No. 216,747.

To all whom it may concern:

Be it known that I, JAMES N. GIBSON, a citizen of the United States, residing in Greeley, in the county of Weld and State of Colorado, have invented certain new and useful Improvements in Oil-Tanks for Delivery-Wagons, of which the following is a specification, reference being had to the accompanying drawings, forming a part thereof.

10 My invention consists in a combined oil tank and measuring vessel adapted to be secured to the under side of a wagon-body, preferably at the rear end thereof, thus avoiding the danger of contamination of other articles 15 in the wagon from contact with the oil and avoiding the necessity of loading customers' oil-cans into the wagon to be filled and returned.

In the accompanying drawings, Figure 1 20 is a rear elevation of a wagon provided with my oil-tank, and Fig. 2 is a vertical transverse section of the storage-tank and the measuring-tank.

A designates the wagon, and B the rear axle 25 thereof.

To the under side of the wagon-body A and preferably to the rear of the axle B is secured the closed storage-tank 1, preferably made of sheet metal in substantially the form shown.

30 The storage-tank 1 may be secured to the wagon-body by means of straps 2 and bolts 3 or in any other desired manner. At one end the storage-tank 1 is provided with a filling-pipe 4, adapted to be closed by a cap 5, 35 and with a gage-glass 6 of usual construction to indicate the level of the oil in the storage-tank.

To the under side of the storage-tank 1 is secured the measuring-tank 7, which is preferably made in the form of a cylinder with closed ends and suspended from the storage-tank by straps 8, of metal or other suitable material. The measuring-tank 7 communicates with the supply-tank 1 by means of a 45 pipe 9, provided with a valve 10, and at its bottom is provided with a discharge-valve 11, to which is attached a flexible tube of rubber or other suitable material, through which the measured oil may be discharged into the customer's can 13. The tube 12 when not in

use is held by the clip 14, secured to the top of the measuring-tank 7.

The measuring-tank 7 is provided with an inspection-tube 15, extending through the top thereof and preferably located near the center of the measuring-tank 7, as shown. This inspection-tube 15 is provided with a hinged lid 16, normally held closed by a spring 17. It is also cut away at one or both sides, as at 18, and is provided with cross-bars 19 and 20. 60 The measuring-tank 7 is preferably made to hold one gallon of oil when filled to the level of the bar 20, and the bar 19 is so positioned therein as to indicate half a gallon when the tank is filled so that the oil stands at its level. 65

The operation is as follows: The storage-tank 1 is first filled with oil through the tube 4, and the cap 5 is placed thereon. The measuring of the oil is unnecessary, as the gage-glass 6 shows the level of the oil in the storage-tank. The oil is now contained in the tightly-closed storage-tank 1 and may be transported without the slightest danger of contaminating the goods carried in the wagon A. When a sale of oil is made, the valve 11 75 being closed and the cover 16 being raised, the valve 10 is opened and oil is allowed to flow from the storage-tank 1 into the measuring-tank 7 until it reaches the level of the bar 19 or the bar 20, as desired. The valve 10 is then closed, and the tube 12 being placed in the customer's can the valve 11 is opened and the measured oil is allowed to run thereinto.

While I have shown the preferred form of 85 my invention, I do not desire to be limited to the exact details thereof, as many slight modifications may be made therein without departing from the spirit of my invention.

Having now described my invention, what 90 I claim, and desire to secure by Letters Patent, is—

In an oil-tank for delivery-wagons, the combination with a storage-tank, adapted to be secured to the under side of an ordinary 95 wagon-body, said storage-tank being provided with a gage-glass and a filling-tube adapted to be closed by a cap, of a horizontally-arranged cylindrical measuring-tank suspended therefrom and communicating there- 100

with through a valved pipe, said measuring-tank being provided with an inspection-tube in its top, said inspection-tube being provided with a hinged lid normally held closed by a spring, and with one or more devices on the interior thereof for indicating the level of the oil in said measuring-tank, a valved discharge-tube leading from the bottom of said measuring-tank, and a clip for holding said dis-

charge-tube when not in use, substantially as 10 described.

In testimony whereof I have signed my name to this specification in the presence of two subscribing witnesses.

JAMES N. GIBSON.
